UNITED STATES PATENT OFFICE

EMIL KERN, OF FLUSHING, NEW YORK, ASSIGNOR TO ACCO PRODUCTS, INC., OF LONG ISLAND CITY, NEW YORK, A CORPORATION OF NEW YORK

FASTENER

Application filed December 22, 1930. Serial No. 503,865.

This invention relates to fasteners which are used to secure letters, documents and the like for filing, and particularly to fasteners having two spaced tongues which pass through the papers to be secured and through similarly spaced perforations in a retainer or keeper over which the tongues are bent.

It is the object of the present invention to provide a simple and effective fastener 10 which will hold the assembled papers securely, can be manipulated easily, and is light and nevertheless sufficiently stiff.

Other objects and advantages of the invention will be indicated as it is described 15 in the following specification with reference to the accompanying drawings, in which

Fig. 1 is a plan view of the fastener showing the application thereof to the papers;

Fig. 2 is an enlarged section on the line 20 2-2 of Fig. 1;

Fig. 3 is an enlarged section on the line 3-3 of Fig. 1;

Fig. 4 is a sectional view similar to Fig. 3, illustrating the operation of the fastener; 25 Fig. 5 is an enlarged sectional view illustrating the method of unlocking the tongues;

Fig. 6 is a view in perspective of the fastener;

Fig. 7 is an enlarged sectional view of a 30 slightly modified form of the fastener;

Fig. 8 is a view in perspective of a slightly modified form of the keeper; and

Fig. 9 is a similar view of another form of the keeper.

Referring to the drawings, 5 indicates the base of a fastener having spaced tongues 6 formed integrally therewith and adapted to be bent as indicated to pass through a file of papers 7. The ends of the tongues 6 project through perforations 8 near the ends of a keeper 9 which rests upon the uppermost paper of the file.

The keeper 9 consists of a strip of metal 45 having two longitudinal ribs 10 on the upper surface thereof, the ribs being formed by pressing or otherwise forcing up the body of the strip. Flanges 10' are shaped to engage the papers 7. The keeper is provided with the perforations 8 hereinbefore mentioned.

To permit locking of the tongues 6 after they have passed through the perforations 8, the ribs 10 are preferably formed as indicated in Figs. 3, 4 and 5, that is to say, they are curved inwardly, or toward each other, approaching the top of the ribs so as to afford a recess at the bottom of the keeper slightly wider than the shortest distance between the opposed surfaces of the ribs, so that the tongue 6 when bent and pressed 55 downwardly as indicated in Fig. 4 may be forced past the projecting rounded surfaces of the ribs into the recess, in which they are firmly locked. The natural resiliency of the metal when bent in the form indicated in 60 Figs. 3, 4 and 5, permits the ribs to spring apart slightly when the tongues are forced downwardly, so that the tongues readily pass into the recess. The necessary curvature of the ribs is slightly exaggerated in Figs. 3, 65 4 and 5 of the drawings for the purpose of illustration. The natural resiliency of the metal may be augmented by providing a longitudinal slot 11 in the metal at the bottom of the recess. When the tongues 6 are forced 70 into the recess of the keeper as described, they are securely held so that the fastener is locked and the papers are bound securely.

The locking of the tongues 6 can be facilitated by making them slightly wider at 75 their free ends. Thus, for example, the tongues may taper inwardly from the free ends toward the base, as indicated in Fig. 1 of the drawings. The tapering is exaggerated in the drawings for purposes of illustration. The slightly wider ends of the tongues engage the opposed surfaces of the ribs and are securely held until released in the manner described.

To release the fastener, any suitable instrument may be inserted to spring the ribs slightly and thus permit the withdrawal of the tongues. I prefer to provide the keeper with chamfered ends 12 forming wedges. One of these wedges at the end of a keeper 95 may be employed as indicated in Fig. 5 to spring the ribs and thus to release the tongues 6 from the recess. When released, the tongues can be bent to the upright position as indicated in Fig. 6, and the keeper can then be 100

withdrawn, thus releasing the papers or other documents in the file.

In Fig. 7 of the drawings, I have illustrated a slightly modified form of the invention in which a base 13 is provided with tongues 14 adapted to engage the keeper 15 as in the preferred embodiment. The keeper 15 is provided with ribs 16, the opposite faces of which are substantially straight and spaced a distance corresponding to the width of the tongues 14. In this form of the device, the tongues 14 are bent after they have passed through suitable perforations in the keeper and engage the opposed straight walls of the recess formed by the ribs 16. The width of the tongues 14 and the distance between the opposed faces of the ribs 16 are such that the edges of the tongues engage the opposed faces of the ribs in the recess and are firmly held in locked position. The tongues 14 may be tapered as in the preceding embodiment of the invention. Preferably the keeper is provided with a longitudinal slot 17 to afford additional resiliency. Thus, when the tongues 14 are forced into the recess the ribs may be spread slightly to ensure ample friction. The tongues may be released as in the preceding embodiment of the invention by inserting any suitable instrument such as the wedge formed at the end of the keeper as shown in Fig. 5.

As indicated in Fig. 8 the keeper 18 may be constructed as shown in either Fig. 3 or Fig. 7 except for the omission of the longitudinal slot between the ribs 19 and slots 20 may be formed in the flanges 21. Perforations 22 may be provided to receive the tongues of the fastener as in the preceding embodiments of the invention. In Fig. 9 the structure is as shown in Fig. 8, except for the provision of a plurality of spaced slots 23 in the flanges 21.

The fastener as herein described avoids the necessity for providing slides or other similar locking means on the keeper. The structure and operation of the device are extremely simple.

Various changes may be made within the scope of the accompanying claims without departing from the invention or sacrificing any of the advantages thereof.

I claim:

1. A fastener comprising a base having spaced tongues and a keeper with similarly spaced perforations to receive the tongues, and longitudinal ribs on the keeper forming a recess into which the tongues may be bent; the opposed faces of the recess being adapted to engage and hold the edges of the tongues.
2. A fastener comprising a base having spaced tongues and a keeper with similarly spaced perforations to receive the tongues and a longitudinal slot, and longitudinal ribs on the keeper forming a recess into which the tongues may be bent; the opposed faces of the recess being adapted to engage and hold the edges of the tongues.

of the recess being adapted to engage and hold the edges of the tongues.

3. A fastener comprising a base having spaced tongues and a keeper with similarly spaced perforations to receive the tongues, and longitudinal ribs on the keeper forming a recess into which the tongues may be bent; the opposed faces of the recess being adapted to engage and hold the edges of the tongues, one end of the keeper being wedge-shaped.

4. A fastener comprising a base having spaced tongues and a keeper with similarly spaced perforations to receive the tongues and longitudinal ribs on the keeper forming a recess into which the tongues may be bent; the opposed faces of the recess being curved inwardly toward the top of the recess and adapted to engage and hold the edges of the tongues.

5. A fastener comprising a base having spaced tongues and a keeper with similarly spaced perforations to receive the tongues and a longitudinal slot, and longitudinal ribs on the keeper forming a recess into which the tongues may be bent; the opposed faces of the recess being curved inwardly toward the top of the recess and adapted to engage and hold the edges of the tongues.

6. A fastener comprising a base having spaced tongues and a keeper with similarly spaced perforations to receive the tongues, and longitudinal ribs on the keeper forming a recess into which the tongues may be bent, the opposed faces of the recess being curved inwardly toward the top of the recess and adapted to engage and hold the edges of the tongues, one end of the keeper being wedge-shaped.

7. A fastener comprising a base having spaced tongues wider at their free ends than at the base and a keeper with similarly spaced perforations to receive the tongues, and longitudinal ribs on the keeper forming a recess into which the tongues may be bent; the opposed faces of the recess being adapted to engage and hold the edges of the tongues.

8. A fastener comprising a base having spaced tongues wider at their free ends than at the base and a keeper with similarly spaced perforations to receive the tongues and a longitudinal slot, and longitudinal ribs on the keeper forming a recess into which the tongues may be bent; the opposed faces of the recess being adapted to engage and hold the edges of the tongues.

9. A fastener comprising a base having spaced tongues wider at their free ends than at the base and a keeper with similarly spaced perforations to receive the tongues, and longitudinal ribs on the keeper forming a recess into which the tongues may be bent; the opposed faces of the recess being adapted to engage and hold the edges of the tongues, one end of the keeper being wedge-shaped.

10. A fastener comprising a base having spaced tongues wider at their free ends than at the base and a keeper with similarly spaced perforations to receive the tongues and longitudinal ribs on the keeper forming a recess into which the tongues may be bent; the opposed faces of the recess being curved inwardly toward the top of the recess and adapted to engage and hold the edges of the tongues.
- 15 11. A fastener comprising a base having spaced tongues wider at their free ends than at the base and a keeper with similarly spaced perforations to receive the tongues and a longitudinal slot, and longitudinal ribs on the keeper forming a recess into which the tongues may be bent; the opposed faces of the recess being curved inwardly toward the top of the recess and adapted to engage and hold the edges of the tongues.
- 20 12. A fastener comprising a base having spaced tongues wider at their free ends than at the base and a keeper with similarly spaced perforations to receive the tongues, and longitudinal ribs on the keeper forming a recess into which the tongues may be bent, the opposed faces of the recess being curved inwardly toward the top of the recess and adapted to engage and hold the edges of the tongues, one end of the keeper being wedge-shaped.

In testimony whereof I affix my signature.
EMIL KERN.

DISCLAIMER

1,832,935.—*Emil Kern*, Flushing, N. Y. FASTENER. Patent dated November 24, 1931. Disclaimer filed October 23, 1933, by the assignee, *Acco Products, Inc.*

Hereby disclaims:

From claims 1 and 7 of said Letters Patent, any fastener in which the longitudinal ribs on the keeper are not spaced from the longitudinal edges of the keeper.
